RACKET STRING TIGHTENING MACHINE

Joseph Saladino, Reading, Mass.

Application July 30, 1934, Serial No. 737,562

8 Claims. (Cl. 273—73)

This invention relates to a machine adapted to tighten the playing strings of a tennis, squash, badminton or other racket or bat, which are commonly made of wood, fiber, steel or aluminum.

At the present time rackets are strung by hand and the tightening or tensioning of the strings is accomplished by the operator taking hold of the strings with his hand and repeatedly pulling them, which is difficult and straining work. The degree of tightness of the strings in the racket is to a great extent a matter of guesswork now, as the operator can only estimate their tightness by the sound or pitch resulting from strumming them. Inasmuch as the tightness of the stringing is of great importance, especially to skilled players, it has been, for many years, the constant aim of those in the industry to find a way of stringing rackets to a certain known degree of tightness or tension with all strings alike, which aim is accomplished by my invention.

One object of my invention is to provide a machine which will tighten the playing strings in a racket mechanically thereby doing away with the necessity of pulling them by hand. Another object is to provide such a machine that will determine the degree of tightness of the stringing, so that each string may be tightened to any desired degree, and be uniform with the others. Still another object is to make such a machine simple and speedy in operation and relatively inexpensive to construct and assemble. A further object is to make such a machine adaptable to various sizes and shapes of rackets.

The foregoing and other objects which will appear as the nature of the invention is better understood, may be accomplished by a construction, combination and operative arrangement of parts such as is disclosed by the drawings. The nature of the invention is such as to render it susceptible to various changes and modifications, and, therefore, I am not to be limited to the construction disclosed by the drawings; but am entitled to all such changes therefrom as fall within the scope of my claims.

In the drawings:

Figure 1 is a side elevation view of my racket stringing machine with a tennis racket held thereby for stringing longitudinally.

Figure 2 is a section taken on the line 2—2 of Figure 4 illustrating the side clamp of the racket holder holding a racket.

Figure 3 is a section taken on the line 3—3 of Figure 4 showing the pulley, with cable fastened thereto, of the string tightening device.

Figure 4 is a plan view of my racket stringing machine, the string tightening device being shown in normal position.

Figure 5 is a plan view of my racket stringing machine with a tennis racket held thereon for

stringing laterally, and showing the string tightening device in actuated position.

Figure 6 is a section taken on the line 6—6 of Figure 4, illustrating the mechanism of the string tightening device in detail.

Figure 7 is a section taken on the line 7—7 of Figure 4 showing details of the pawl and ratchet of the string tightening device.

Figure 8 is a section taken on the line 8—8 of Figure 5 showing the barrel member of the string 10 tightening device.

Figure 9 is a plan view of my racket stringing machine in actuated position, showing an insert holder which is used to accommodate the smaller size rackets.

Figure 10 is a section taken on the line 10—10 of Figure 9 showing the clamping means with the racket holder in detail with the insert holder in position.

Figure 11 is a section taken on the line 11—11 20 of Figure 9, the view being similar to Figure 2, illustrating the side clamp of the racket holder with the insert holder in place.

As illustrated my machine has a supporting stand or base 15 having a bossed portion 16 into 25 which a vertical standard 17 fits. Attached to said standard 17 by screws 19 is a guide bracket 18, and extending between said bracket 18 and said standard 17 is a treadle 21 pivoted as at 22 to a yoke 23 which screws into said base 15. Said 30 treadle 21 has a foot lever 25 affixed thereto by screws 26, pressure on which foot lever 25 actuates the string tightening device later described.

Adjustably mounted on said treadle 21 is a block 28 held by a thumb screw 29 in any desired 35 position. An eye member 30 fits in said block 28 to receive a cable or belt 31 which passes over a pulley, later described, and is fastened at the other end to a spring 32 which in turn is fastened to one of said screws 19 which hold the guide 40 bracket 18.

Said standard 17 telescopically engages a vertical sleeve 34, and is held in any desired position by a hand screw 35, so that the height of my machine may be adjusted vertically to the convenience of the operator. Mounted on said sleeve 34 is a tool support or table 36. A bracket 38 is fastened to said sleeve 34 by a set screw 39, and said bracket 38 has an arm or upstanding part 40 which supports the string tightening device 50 64 later described.

A holder 42 supports and holds the racket 49, and is rotatable so that the position of said racket may be changed as the stringing proceeds. For instance, when the longitudinal stringing is done 55 the racket is held in the position shown in Figure 1 of the drawings, while the cross stringing is done with the racket held in the position shown in Figure 5 of the drawings. Said holder 42 consists of a supporting frame 43 which is rotatably 60

mounted on said bracket 38, being rotatable about bearings 44. A cap or plate 45 rests on the bottom of said frame 43 and is held to said bracket 38 by a large screw 46. Said holder 42 has a top 48 which is integral with said frame 43 on which the tennis racket 49 or other playing instrument rests while being strung. The ordinary racket consists of a curved portion known as the bow head, which receives the stringing, and a straight handle, as illustrated in Figure 5 of the drawings.

To hold said racket 49 in position on said top 48 of said holder 42 there is a hook member or clamp 50 at the rear of said holder 42 which holds the upper head portion of the racket, the hook portion resting on the top face of the racket, being shown at the right in Figure 1 of the drawings. This hook member 50 is held by a thumb screw 51 which screws into the said frame 43, passing through a long vertical slot 52 in said hook member, which slot makes said hook member vertically adjustable so it can be used for rackets of different thickness.

At the lower or throat portion of the head of the racket is a front clamp member 53, which also has a hooked portion 54, which extends above the said top 48 and presses horizontally against said bow head as shown in Figure 1 of the drawings. This clamp member 53 is held by a thumb screw 55 which loosely extends through said member 53 and is threaded into said frame 43, below which is an aligning thumb screw 56 which is threaded into the said clamp member 53, and serves to hold said member 53 straight.

At each side of the said holder 42 are side clamps 57 which hold the racket at each side and which have a hole 59 tapped into them. Said top has projecting portions 58 integral therewith to thereby provide a long slot 61 so that said clamps 57 may be moved horizontally to make adjustments for rackets of various thickness. A thumb screw 60 passes through said slot 61, a portion of which bears against the bottom surface of said top 48 when it is tightened, and said screw 60 enters said hole 59 to thereby prevent any horizontal movement of said clamp 57. As illustrated in Figure 10 of the drawings this slot 61 is oversize with respect to said screw 60 so that some sidewise adjustment is possible, in order that the clamp 57 may be affixed to the racket in such a way that it will avoid covering any of the stringing holes.

The strings in the racket are pulled tight by a rotatable tensioning or tightening device 64 which has a pulley 65 fastened thereto by screws 66 which extend from a ratchet 67 into said pulley. Said pulley 65 has a longitudinal hole 62 extending therethrough as illustrated in Figure 3 of the drawings, through which said cable 31 passes, and set screws 63 are tightened directly against said cable 31 in said hole 62, to thereby hold the cable fast, as it is important that there be no slipping of the cable during the tightening operation. Said device 64 has a ratchet 67 a portion of which has teeth 68. A screw 69 extends through a portion of said ratchet 67 into a horizontal shaft 70 which has a cap 71 at one end integral therewith. A helical spring 72 has one end as at 73 projecting into said cap 71 as best illustrated in Figure 6 of the drawings, the other end 74 passing into a hole in the wall of a barrel 76, which together with said cap 71 encloses said spring 72. A bushing 77, which surrounds a portion of said shaft 70, is made integral with said barrel 76 and rotatably fits into a housing 78

which is an integral extension of said bracket arm 40.

An indicator pointer 79 is fastened to said bracket 40, and as said tightening device 64 is rotatably moved a scale 80, marked on the outside of said barrel 76, rotates therewith, and the numeral on said scale 80 which is opposite the pointer 79 shows to what degree the strings 83 in the racket have been tightened. Usually the strings 83 are tightened in terms of pounds, and the scale 80 ordinarily indicates pounds, although it could indicate other terms as well.

A cleat 81 on said barrel 76 projects slightly above it, being held by a screw 82, and the string 83 from the racket is wound around said cleat 81 to firmly hold it, so that rotation of said tightening device 64 pulls said string 83 tight, and when the indicator pointer 79 indicates on the scale 80 that the string has been tightened to the point desired, the string is held by inserting an awl or other pointed instrument in the racket hole through which the string 83 passes on its way to the tightening device 64.

As will be seen, when the treadle 25 is depressed said pulley 65 is rotated, thereby tightening the string 83 from the racket, as the rotation of the pulley rotates said shaft 70 which in turn acts upon said spring 72 to rotate said barrel 76, and the scale 80 marked thereon.

In order that my machine may not only take one type of a racket such as a tennis racket, I provide an insert holder 87 in order that smaller rackets such as squash and badminton rackets may be strung. Said insert holder 87 is supported by said top 48 by an overhanging or ledge portion 88 which rests on said top. The inside shape of said insert holder 87 is the same shape as the racket to be strung, and I have illustrated in Figure 9 of the drawings an insert holder to take a squash racket 89. This insert holder 87 is readily inserted by unscrewing the clamps which hold the racket, and when the insert holder 87 is in place the clamps are tightened in the same manner as for the larger racket.

A pawl 91 having a tooth 92 which engages the toothed portion 68 of the ratchet 67 pivots on a pin 93 which enters said bracket arm 40. A spring 94 is fastened at the free end of said pawl 91, which spring is fastened by a screw 95 to a portion of said bracket arm 40, and serves to keep the tooth 92 in position to normally engage the toothed portion 68 when it is presented to it. A handle 96 is fastened to said pawl 91 in order that said tooth 92 may be moved out of engagement with said toothed portion 68 of the ratchet when it is desired to have the tightening device 64 return to normal position. A stop pin 97 in the bracket arm 40 projects outwardly whereby the movement of said handle 96 is limited when pulling said tooth 92 out of engagement, as previously described. A stop member 98 on said ratchet 67 determines the normal position of said ratchet, and normally the said stop member 98 and said tooth 92 abut one another, as shown in Figure 7 of the drawings, thereby preventing any further clockwise movement of said ratchet.

To operate my machine the racket is laid on the top 48 and the clamps tightened against different portions of the bow head. The string 83 is inserted in holes in the said racket and when said string 83 comes through the hole in the racket nearest the tightening device it is wound around said cleat 81, the foot lever 25 of the treadle is pressed, thereby rotating said tightening device and pulling on said string 83 until it 75

is drawn sufficiently tight, then the string is held by inserting an instrument in the said hole in the racket, whereupon the foot lever is released, and the handle 96 is moved sufficiently to release 5 the tooth 92 from the toothed portion 68 of the ratchet 67, and the tension of the spring 72 causes said tightening device to return to normal position. The string 83 is then unwound from the cleat 81 and inserted through the next holes 10 in the racket and the operation repeated. When the racket is ready for cross stringing the holder is rotated sufficiently so that the direction of the stringing to be done is towards the tightening device 64.

15 The construction should be noted wherein the top of the string tightening device 64 is lower than the top 48 so that the handle of the racket to be strung will not interfere with the operation of said device.

20 Through being able to determine the tightness of each string my machine makes it possible to preserve the original shape of the racket bow head, whereas when the stringing is done by hand the fact that frequently one string is tighter than 25 another pulls the bow head out of shape.

What I claim is:

1. A racket string tightening machine comprising in combination, supporting means adapted to support the racket to be strung, mechanism in 30 juxtaposition to said means adapted upon actuation to tighten a string in a racket, and instrumentalities connected to and adapted upon actuation to actuate said mechanism to thereby tighten said string, said supporting means embodying a support for the racket, clamping means to hold the racket fast, and an insert 35 holder supported by said support, and adapted to receive said clamping means, said clamping means embodying members adapted to pass through said insert holder and engage with said support to thereby hold the racket to be strung in said insert holder.

2. A racket string tightening machine comprising in combination, supporting means for a 45 racket, a rotatable device adapted to receive and tighten a string in a racket supported by said means, and instrumentalities operatively connected to said device adapted upon actuation to rotate said device to thereby tighten said 50 string, said device embodying a pulley, a ratchet adapted to hold said pulley in actuated position, a barrel, a spring in said barrel, and a shaft extending from said pulley into said barrel, and means interconnecting said pulley, ratchet, barrel, spring and shaft whereby rotation of said 55 pulley actuates said shaft, ratchet, spring and barrel.

3. A racket string tightening machine comprising in combination, supporting means for a 60 racket, a rotatable device adapted to receive and tighten a string in a racket supported by said means, and instrumentalities operatively connected to said device adapted upon actuation to rotate said device to thereby tighten said 65 string embodying a cable, said device embodying a pulley adapted to receive said cable, a barrel, a spring, and a shaft extending from said pulley through said barrel embodying a cap, said barrel and said cap having provision to receive an end of said spring, and means interconnecting said 70 pulley, barrel, spring and shaft whereby rotation of said pulley actuates said device.

4. A racket string tightening machine compris-

ing in combination, supporting means for a racket, a rotatable device adapted to receive and tighten a string in a racket supported by said means, and instrumentalities operatively connected to said device adapted upon actuation to rotate said device to thereby tighten said string embodying a treadle and cable fastened to said treadle, said device embodying a pulley adapted to receive said cable, a barrel embodying means adapted to hold said string, and means operatively connecting said pulley and barrel whereby actuation of said pulley rotates said barrel to thereby tighten said string.

5. A racket string tightening machine comprising in combination supporting means for a racket, a rotatable device adapted to receive and tighten a string in a racket adjacent said means, and instrumentalities operatively connected to said device adapted upon actuation to rotate said device to thereby tighten said string, said device embodying a pulley adapted to receive and be actuated by said instrumentalities, a barrel, a coiled spring extending horizontally in said barrel, a shaft extending from said pulley through said spring and projecting beyond, said shaft embodying a cap at one end having provision to receive an end of said spring, said barrel having provision to receive the other end of said spring, and means to hold said pulley and shaft together to thereby operatively interconnect said pulley, barrel, spring and shaft whereby rotation of said 25 pulley actuates said device.

6. A racket string tightening machine comprising in combination, supporting means for a racket, a rotatable device adapted to receive and tighten a string in a racket supported by said means, and instrumentalities operatively connected to said device adapted upon actuating to rotate said device to thereby tighten said string, said device embodying a spring connected to said rotatable device, and means operatively connecting said instrumentalities to said spring whereby actuation of said instrumentalities tensions said 30 spring and thereby rotates said rotatable device.

7. A racket string tightening machine comprising in combination, supporting means for a 45 racket, a rotatable device adapted to receive and tighten a string in a racket supported by said means, and instrumentalities operatively connected to said device adapted upon actuation to rotate said device to thereby tighten said string, said device embodying a spring connected to said rotatable device, means adapted to hold said device in tensioned position, and means operatively connecting said instrumentalities to said spring whereby actuation of said instrumentalities tensions said 50 spring and thereby rotates said rotatable device.

8. A racket string tightening machine comprising in combination, supporting means for a 60 racket, a rotatable device adapted to receive and tighten a string in a racket supported by said means, instrumentalities operatively connected to said device to thereby tighten said string embodying a cable and means to actuate said cable to thereby rotate said device, said device embodying a pulley adapted to receive and be actuated by said cable, and a spring adapted to be tensioned, and means operatively connecting said spring to said rotatable device and to said cable whereby the actuation of said cable tensions said 65 spring and rotates said device.

JOSEPH SALADINO.
